Des. 225,088
Patented Nov. 7, 1972

225,088

THERAPEUTIC CAP

Ashsha East, 7140 N. Federal,
Westminster, Colo. 80030

Filed July 2, 1970, Ser. No. 23,802

Term of patent 14 years

Int. Cl. D24—04

U.S. Cl. D83—1

FIG. 1

FIG. 2

FIG. 3

FIG. 1 is a side elevational view of a therapeutic cap showing my new design, the side opposite that shown being a mirror image thereof;

FIG. 2 is a back elevational view thereof; and

FIG. 3 is a front elevational view thereof.

I claim:

The ornamental design for a therapeutic cap, as shown.
